Patented Mar. 27, 1973

226,560

AMMUNITION MAGAZINE

Leroy James Sullivan, Orange, Calif., assignor to J. Robert Egan, Newport Beach, John Wayne, Beverly Hills, and Robert L. Gaddis, Marie Lyon Gaddis, and Leroy James Sullivan, Huntington Beach, Calif., fractional part interest to each

Filed Dec. 9, 1970, Ser. No. 26,378

Term of patent 14 years

Int. Cl. D22—03

U.S. Cl. D22—7

FIG. 1 is a side elevational view of an ammunition magazine showing my new design;

FIG. 2 is a top plan view thereof;

FIG. 3 is a rear elevational view thereof as seen from line 3 in FIG. 1;

FIG. 4 is a front elevational view thereof as seen from line 4 in FIG. 1.

I claim:

The ornamental design for an ammunition magazine, as shown and described.
